UNITED STATES PATENT OFFICE.

ALLAN G. MATHER AND ERNEST C. SHAW, OF MILWAUKEE, WISCONSIN.

TEMPERATURE-CONTROLLING DEVICE FOR FURNACES.

No. 874,781.

Specification of Letters Patent.

Patented Dec. 24, 1907.

Application filed April 7, 1905, Serial No. 254,303. Renewed November 14, 1907. Serial No. 402,210.

To all whom it may concern:

Be it known that we, ALLAN G. MATHER and ERNEST C. SHAW, citizens of the United States, residing at Milwaukee, county of Milwaukee, and State of Wisconsin, have invented new and useful Improvements in Temperature-Controlling Devices for Furnaces, of which the following is a specification.

10 Our invention relates to improvements in temperature controlling devices for furnaces.

The object of our invention is to provide reliable electromagnetic mechanism, having a thermostatic circuit closer for controlling 15 the operation of a motor which is connected to open and close the draft and check dampers of a furnace in alternation.

In the following description reference is had to the accompanying drawings, in which 20 Figure 1 is a front elevation of our invention with part of the casing removed. Fig. 2 is a horizontal sectional view of the same, drawn on line $x-x$ of Fig. 1. Fig. 3 is a general view illustrating the application of our 25 invention to a furnace.

1 is a driving shaft extending through a box or casing 2 and provided with cranks 3 & 4 on its projecting ends, which are connected respectively with a check damper 5 and draft damper 6 by means of cords or chains 7, the latter being preferably passed over suitable guide pulleys at 8, as shown in Fig. 3. The cranks 3 & 4 project in opposite directions from the shaft 1, so that the dampers 5 & 6 will be opened and closed in alternation. A sprocket wheel 10 is loosely mounted on the shaft 1 and is provided with a clutch member 11, which is adapted to engage a clutch member 12, fixed 35 on the shaft 1 whereby the shaft 1 may be driven in one direction from the sprocket wheel 10. The clutch members are arranged to slip when the motion of the sprocket wheel 10 is reversed and the sprocket 40 wheel 10 is normally held in position with the clutch members in engagement by means of a spring 13. The sprocket wheel is driven by a weight 14 through a chain 15, which passes around a suitable pulley 16, connected with 45 the weight 14 and also over the wheel 10. A disk 20 is driven from the shaft 1 through the medium of the gear wheel 21, pinion 22, gear wheel 23, pinion 24 and shaft 25, the disk 20 being mounted upon the latter. The parts 50 are, however, normally held against movement by means of a brake lever 27, which is

provided with a notch 28 near one end, in which the edge of the disk 20 is engaged, so that when the other end of the lever is depressed, the opposing sides of the notch 28 will be brought into binding engagement with the disk to hold it against rotation. The lever 27, at a point distant from the notch 28, is connected with an armature bar 30 by means of an adjustable screw threaded post 31, so that this end of the lever may be raised or lowered by means of said armature bar 30. The notched end of the lever is loosely supported by an insulated rest 33.

The armature bar 30 is actuated by gravity in one direction, and in the other direction by electro magnets 35, an electrical circuit through said magnets being closed by means of a thermostatic switch 36 operating between contact terminals 37 and 38 respectively and the connections being such that when the thermostatic switch 36 contacts with either of the terminals 37 and 38, an electrical circuit will be closed through the magnet 35 from a source of electrical energy represented in the drawings by a battery 39. This battery has one pole connected with the thermostatic switch 36 by means of a conductor 40. A conductor 41 of opposite polarity leads from the battery to the electro magnet 35 coils and through them to the frame or box 2. The terminals 37 & 38 are electrically connected by means of conductors 43 & 44 with commutator brushes 45 & 46 respectively, the latter being mounted in, but insulated from the box 2. These brushes 45 & 46 are arranged to bear upon a hub 47 of the clutch member 12, (the hub being provided with slight grooves for the reception of the brushes) and a comparatively short section of insulation 49 is located in each of these grooves, whereby the circuit will be broken between the hub 47 and a registering brush when the corresponding section of insulation is interposed between such brush and the hub 47. The insulation 49 which registers with the brush 45 is on the opposite side of the hub 47 from that which registers with the brush 46, so that the circuit through the brushes will be broken alternately during the rotation of shaft 1, and will be broken once through each brush during one complete rotation of the shaft.

Assuming the parts to be in the position in which they are shown in Figs. 1 & 3, it will be observed that the draft door 6 is open and the thermostatic switch 36 is out

2 . . . . .
 of contact with either of the terminals 37 or 38; the circuit being broken, the armature 30 is depressed by gravity and the brake lever 27 grips the disk 20 and prevents the 5 disk, the intermediate parts, and shaft 1 from rotating under the pull exerted by the weight 12. The brush 46 is in circuit closing position. As the heat increases, the switch 36 moves into contact with the terminal 37 and the circuit of the battery 39 is thereupon closed through the switch, the terminal 37, conductor 43, commutator brush 46, hub 47 and the frame, the electro magnet, and conductor 41, thus energizing 10 the magnets, lifting the armature bar 30 and lever 27 and releasing the disk 20, whereupon the weight 14 will actuate the shaft 1 until the brush 46 registers with the corresponding insulation 49, which separates 15 it electrically from the hub 47, thus breaking the circuit and permitting the armature bar to drop and set the brake on the disk 20; the shaft 1 having completed a one-half revolution, the damper 6 will then be closed and 20 25 the damper 5 opened, thus checking the fire in the furnace.

As the heat decreases, the switch 36 slowly moves across the intervening space until it contacts with the terminal 38, whereupon 30 the circuit is again closed, but this time it is closed through the commutator brush 45, and the shaft 1 is permitted to rotate another one-half revolution, when the circuit is again broken by insulation 49, registering 35 with the brush 45,—the dampers being meanwhile restored to the position in which they are shown in Fig. 3.

The weight 14 may be manually raised from time to time by pulling upon the free 40 end of the chain 15.

Having thus described our invention what we claim as new and desire to secure by Letters Patent is,

1. The combination with the draft and 45 check dampers of a furnace, of a crank shaft provided with oppositely projecting cranks connected with the respective dampers, a sprocket wheel loose on the crank shaft and provided with a one-way acting clutch mem- 50 ber, a weight provided with a sprocket wheel, a sprocket chain passing around said sprocket wheels and connected at one end to a fixed point of support, a clutch member fixed on said crank shaft and adapted to be 55 engaged by the clutch member on the

sprocket wheel when the latter is turned in the direction of the pull exerted by the weight, a spring arranged to normally hold said clutch members in mutually engaging contact, a brake mechanism normally preventing the rotation of said crank shaft, a thermostatic switch, and an electrically operated device for releasing said brake mechanism when the circuit is closed by said switch, and devices carried by the crank shaft for breaking said electrical circuit.

2. The combination with the draft and check dampers of a furnace: of a motor arranged to open and close the said dampers in succession; a rotary disk driven by said motor; and a gravity actuated brake lever provided with a notch in which the margin of said disk is entered; said brake lever being pivotally supported at one end near the notch and normally adapted to drop by gravity to an angular position with the sides of said notch binding upon the disk; an electro-magnet provided with a movable armature; a screw adjustably connecting said armature with the brake lever; a thermostatic switch for closing electrical circuits through the electro-magnet; and means, operated by the motor, for breaking such circuits.

3. The combination with the draft and check dampers of a furnace of a crank shaft 85 provided with oppositely disposed cranks connected to the respective dampers, fast and loose clutch members mounted on the crank shaft, a sprocket wheel mounted on the loose clutch member, a weight provided 90 with a corresponding sprocket wheel, a chain passed around said sprocket wheels and having one end connected with a fixed point of support above the weight, a thermostatic switch, and means, in operative relation 95 thereto, for releasing and holding the crank shaft, said clutch members being arranged for motion transmitting engagement in one direction only, whereby said weight may be periodically lifted by pulling upon the 100 sprocket chain in the opposite direction without operating the crank shaft.

In testimony whereof we affix our signatures in the presence of two witnesses.
